UNITED STATES PATENT OFFICE

CHARLES LANGE, OF CHICAGO, ILLINOIS, ASSIGNOR TO CITRONESIA COMPANY, INC., OF CHICAGO, ILLINOIS, A CORPORATION OF ILLINOIS

DESIGN FOR A BOTTLE

Application filed December 12, 1929. Serial No. 33,758. Term of patent 14 years.

To all whom it may concern:

Be it known that I, CHARLES LANGE, a citizen of the United States, residing in Chicago, in the county of Cook and State of Illinois, have invented a new, original, and ornamental Design for a Bottle, of which the following is a specification, reference being had to the accompanying drawings, forming a part thereof, and in which—

Fig. 1 is a front elevation of the bottle showing the front face thereof and showing my new design.

Fig. 2 is a side elevational view of the bottle taken at ninety degrees angle to Fig. 1 and showing the projecting ridges of the design and bottle surface.

Fig. 3 is a cross sectional view of the bottle taken on line 3—3 of Fig. 1.

I claim:

The ornamental design for a bottle, as shown.

CHARLES LANGE.
